CLAIM

The ornamental design for a motion controller, as shown and described.

DESCRIPTION

FIG. 1 is a perspective view of a motion controller;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof; and,
FIG. 7 is a bottom plan view thereof.

(Continued)

The even broken lines in the figures show portions of the motion controller that form no part of the claimed design. The uneven broken lines in the figures show boundaries of the claimed design.

The claimed design extends to the boundary lines but does not include the boundary lines.
